UNITED STATES PATENT OFFICE.

HARRY J. WARTHEN, OF WASHINGTON, DISTRICT OF COLUMBIA, ASSIGNOR OF ONE-THIRD TO ANDREW J. HURLEY AND ONE-THIRD TO WALTER A. REISS, BOTH OF WASHINGTON, DISTRICT OF COLUMBIA.

ELECTRIC SIGNALING SYSTEM FOR RAILWAYS.

No. 870,145.

Specification of Letters Patent.

Patented Nov. 5, 1907.

Application filed January 18, 1907. Serial No. 362,897.

To all whom it may concern:

Be it known that I, HARRY J. WARTHEN, a citizen of the United States of America, and a resident of Washington, in the District of Columbia, have invented certain new and useful Improvements in Electric Signaling Systems for Railways, of which the following is a specification.

This invention relates to certain new and useful improvements in electric railway-signaling systems of that class in which provision is made for actuating a visible and an audible signal in the cab of an engine to indicate danger or safety.

The present invention has for its objects among others to provide an improved, simple yet reliable and efficient electrical signaling device for railway trains whereby the engineer is automatically notified of danger as well as safety by means situated in the cab of the engine.

It further provides for automatic means for recording the exact time at which the signal was received in the cab and also the length of time the train is running after the receipt of such signal. The recording means is disposed within a suitable box or receptacle which is designed to be locked and access thereto had only by the train despatcher or other authorized person, and not accessible to the engineer or fireman on the engine. In this way all signals received in the cab are automatically indicated and registered. This mechanism comprises broadly changeable paper dials operated by clockwork, and red and blue, or any other differently colored pencils or marking devices placed in independent circuits. The red light is arranged on the red pencil circuit, and a white light on the blue pencil circuit. A switch is employed, which is controlled by a solenoid arranged on the primary circuit. Normally the switch is on the white light circuit contact and indicates safety. When, from any cause, the solenoid becomes sufficiently energized, it pulls the switch over, breaking the white light circuit and closing the red light circuit, thus showing a red light in the cab and indicating danger. A bell or other audible signal is placed in the red light circuit so that when the said circuit is completed the signal is sounded simultaneously with the showing of the red light in the cab.

45 A galvanometer is employed, as well as a telephone on the cab, both being in circuit and serving an important function as will be more fully hereinafter set forth.

The system is divided into two circuits, primary and 50 secondary. The primary circuit consists of a set of batteries in series with solenoid or relay, from thence to the track, the other lead running from the batteries direct to the plow or trolley located under the engine at the

most practical place, the same making electrical contact with a third rail; located on the same circuit is a 55 galvanometer and small magnet, the former, a sensitive electrical needle, which, when connected to electrical circuits, indicates the presence of the smallest appreciable current, and is here applied for the benefit of the engineer as one means of ascertaining the fact as to 60 whether there is current in the third rail, it also indicates to him whether or not the train which has given him the danger signal, is at a standstill; provided it was approaching him, the needle, (in consequence of increased electrical current which would follow by cutting down the rail resistance), would continue to move. The object of the latter, is to hold the contact on the white light circuit point of the secondary batteries, so when there is no current in the primary circuit the magnet allows the contact to break, thus, showing no 65 current in the third rail by the white light no longer burning, this showing danger. The primary circuit is also provided with a single pole switch, the line being broken and run through said switch, from the same two points of the switch wires run to the telephone. When 70 the switch is closed, the current from the primary batteries does not pass through the telephone, but when the switch is open the telephone is thrown into the primary circuit. The telephone is also provided with a closed circuit push button, so that the engineer upon 75 opening the switch can signal along the line, calling up whom he wishes, by pushing closed circuit button, which causes bells to tap and lights to flash alternately from red to white, in every equipment.

The secondary circuit current has two leads, one from 80 the safety point on the solenoid switch, through the magnet contact on the primary circuit, to the blue pencil magnet and on to the white light to the battery; another lead runs from the danger point on the solenoid switch, to the red pencil magnet, to the red light and 85 into the same pole of the battery; the other battery lead, runs to the switch on the solenoid. On this circuit is located a bell, one lead of which runs to an independent point on the danger point of the solenoid switch and the other lead to the opposite battery pole. 90

An essential feature of this invention is the third rail which controls and regulates the manipulation of all the above mentioned devices, which is made possible by the following construction. This rail is placed in the most practical position, for instance midway between the tracks and running parallel with the tracks the entire distance of the divisions. This rail is broken up into what will be known as blocks, which will be from 1½ to 2 miles apart or as far as conditions might demand. Where the rail is broken to form a block, an 100 iron-clad resistance is installed so as to be in series with

and on a level with the rail. The strength of resistances is to be determined by the distance between the blocks. It is evident that when each engine is equipped with the above named appliances and such 5 appliances are in electrical circuit with the third rail and the distance between engines on the same track is such that two or more resistances are in the circuit, that the batteries in both engines are overcome to such an extent that the solenoids or relays cannot operate 10 but the instant the engines approach to that point where only one resistance separates them in the circuit both solenoids or relays are energized and manipulate automatically the secondary circuit.

All signal towers should be equipped with the same 15 appliances, which makes it possible for the tower operator to manipulate through his closed circuit push button the signals in the cab of the engine and converse with the engineer through the telephone.

Another important feature of the invention is the 20 switch signal. The third rail of the siding where it lies between the main tracks is connected by a movable joint to the wheel rail of the main track, the other end is connected to the switch plunger making its movement and position in perfect relation to the wheel 25 switch. An inclined contact plate is attached to the third rail of the main road; when the switch is closed the third rail then connected on movable joint breaks contact, but when switch is open this piece of rail is forced upon the contact plate, short circuiting the 30 block, by connecting the positive current of the third rail with the negative of wheel rail, so when an approaching train enters a block, the engineer is notified by red light and bell that the switch is open, or by white light, if closed.

35 A wire connection is run from the third rail of the main line to the third rail of the siding track, so when an engine is on the siding the apparatus is in the same electrical relation with the main track, as if it were on the main road, thus giving the engineer warning if track 40 is clear before proceeding to open switch and enter on track.

A train can always be signaled by short circuiting from the third rail to wheel rail with a wire, or a crow-bar, or anything of like nature, which will show the 45 red light and ring the bell when engine enters block.

Other objects and advantages of the invention will hereinafter appear and the novel features thereof will be particularly pointed out in the appended claims.

The invention, in its preferred form, is clearly illustrated in the accompanying drawings, which, with the 50 numerals of reference marked thereon, form a part of this specification, and in which

Figure 1 is a diagrammatic view showing the apparatus as arranged on two cabs, and showing also the third 55 rail and its resistances. Fig. 2 is an enlarged diagrammatic view of the appliances carried by the cab. Fig. 3 shows in perspective the inclosure for the recording mechanism, and diagrammatically the galvanometer and the telephone and its connections. Fig. 4 is an 60 enlarged detail in elevation of one of the pencils and its supporting and actuating devices, with portions broken away and a part in section. Fig. 5 is a top plan of the nut locking member thereof. Fig. 6 is an enlarged section on the line 6—6 of Fig. 4, with parts in elevation and broken away. Fig. 7 is an enlarged detail of

the pencil-holding device, with the pencil shown in cross section. Fig. 8 is an enlarged horizontal longitudinal section through one of the third rail resistances, showing also adjacent portions of the rail and their connections. Fig. 9 is a vertical cross section as on the line 9—9 of Fig. 8. Fig. 10 is an enlarged detail of the contact shoe and its support and buffer. Fig. 11 is an elevation showing a modified form of contact device. Fig. 12 is a vertical section on the line 12—12 of Fig. 10. Fig. 13 is a plan view of the third rail switch. Fig. 14 is an enlarged section on the line 14—14 of Fig. 13.

Like numerals of reference indicate like parts throughout the several views.

In carrying out the invention there are employed certain elements, such as a solenoid, a telephone, a dial rotated by clockwork, and markers acting in conjunction therewith to record the signals, and these have been shown of the conventional form, it being understood that the present invention is in no wise restricted to any particular construction of these elements, but that any well known or approved forms may be employed.

Referring now to the drawings 1 designates the rails upon which travel the wheels 2 of the engine, of which 3 designates the axle. As the present invention is applicable to the ordinary, or any form of engine, requiring no special construction thereof, and as the various parts located on the cab may be disposed in any desired or convenient location thereon, it has not been deemed necessary to illustrate the cab, but it is thought 95 to be sufficient to show the present improvement in a diagrammatic way.

4 is the third rail, which controls and regulates the manipulation of the various elements hereinafter described. It may be disposed where found most desirable or practicable, in the present instance located substantially midway between the rails 1, 1, and running parallel therewith the entire distance of the road which is equipped with this system. This third rail is broken up into what is known in railroad parlance 100 as "blocks". Whenever the rail is broken to form a block, an iron clad resistance is installed so as to be in series with and on a level with said third rail. The strength of the resistances will be determined by the length of the block, that is the distance between the 105 resistances. In Figs. 8 and 9 one of these resistances is shown in enlarged detail. It comprises essentially a

box 5 having at one end a lug 6 which is received between clamping plates 7 with suitable insulation 8, the said plates embracing the adjacent end of the adjacent rail 4, the said plates and the lug 6 being secured together by the transverse bolt 9. The upper face of the box is formed with the centrally-located portion 10 of the same width as the upper surface of the rails 4, to form a continuation thereof. Within this box is the 110 resistance coil 11, one end of which is connected with the bolt 9, and the other end having connection, as at 12, with the rail 4 at the opposite end of the box. The ends of the coil pass through suitable openings in the walls of the box as indicated clearly in Fig. 8.

A contact piece, either a shoe, a wheel, or any other form suitable for the purpose, is carried by the engine and arranged to travel upon the third rail. In Figs. 1 and 2 this contact piece is designated by the numeral 13, it being carried by the shaft or axle 14. One effi-

cient form of contact piece is shown in Fig. 10 in which it is shown in the form of a shoe 13, which is securely bolted or otherwise affixed to the arm 15 pivotally mounted on the shaft or axle 14 which is supported in the ears 16 of a suitable casing having an attaching plate 17 by which it is secured to the under side of the engine frame, and from which it is insulated by suitable insulation 18. This arm 15 is limited in its downward movement by a stop shoulder or the like 19 at the bottom wall of the casing, as seen clearly in Fig. 10. In order to cushion the said shoe and to prevent injury thereto, the arm 15 is provided with the curved and upwardly extended member 20, which is movable through an opening 21 in the bottom of the box or casing 22 beneath the attaching plate 17 and which may or may not be integral with the casing in which the axle 14 is supported.

23 is a head or piston or plunger carried by the member 20 within the box 22, and between said head and the attaching plate 17 is disposed a spring 24 as seen in Fig. 10, for an obvious purpose.

In lieu of a shoe as just described, a wheel 25, as seen in Fig. 11, or any other suitable contact member may be employed. It will be understood that in the form shown in Fig. 11 the arm 15 is mounted and is provided with the cushioning device, the same as in the form illustrated in Fig. 10, the mode of operation being the same in both instances, the wheel being designed to travel on the third rail, as illustrated.

30 The system embodies two electric circuits, a primary and a secondary. The primary circuit consists of a set of batteries 26 in series with a magnet 27 by means of wire 28 and with a solenoid 29 by wire 30 and thence by wire 31 to a galvanometer 32 and thence by wire 33 to a single pole switch 34 connected by wire 35 with the axle 3 of the wheel 2. The other lead runs from the batteries 26 by wire 36 to the contact 13 (or 25), the same making electrical contact with the third rail.

40 37 is a telephone apparatus connected by wires 38 and 39 to the two points of the switch 34, the telephone being provided with a closed circuit push button 40 for a purpose which will hereinafter appear. The galvanometer, when connected in the electrical circuit 45 indicates the presence of the smallest appreciable amount of current, and is provided for the benefit of the engineer, being one means of ascertaining whether or not there is current in the third rail. It serves a so to indicate to the engineer whether or not a train which 50 has given to him the danger signal is at a standstill. If such train were approaching him, the needle, which is very sensitive, would (in consequence of increased electrical current which would follow by cutting down the rail resistance) continue to move. The magnet 27 55 serves to hold the contact on the white light circuit point of the secondary batteries (soon to be described) so that when there is no current in the primary circuit the magnet allows the contact to break, thus showing that there is no current in the third rail, by the white 60 light no longer burning, thus indicating danger.

When the switch 34 is closed the current from the primary batteries does not pass through the telephone, but when the switch is opened the telephone is thrown into the primary circuit. By then pushing the closed circuit button 40 which causes the bells to tap and the

lights to flash alternately from red to white, in every equipment, the engineer can signal along the line, calling up whom he wishes.

It may sometimes be found desirable to place the telephone on an independent circuit, that is on a circuit not including the galvanometer, the solenoid and the magnet 27, but the arrangement shown is believed to be well adapted to the purpose.

41 are the batteries of the secondary circuits. 42 is a bell of ordinary type connected therewith by wire 43, 75 while a wire 44 connects said bell to a contact plate 45 adjacent the solenoid switch 46. This switch is pivotally mounted at 47 and is connected, as at 48, with the core 49 of the solenoid, as seen best in Fig. 2.

50 is a contact point or plate on which the switch 46 80 normally rests and in circuit with the white light and the blue pencil soon to be described.

51 is another contact plate in circuit with the red light and the red pencil, as seen clearly in Fig. 2.

52 is a wire connecting the safety contact point 50 85 with one of the points of the armature 53 of the magnet 27, while 54 is a wire connecting the other point of this armature with the white light mechanism 55, which latter is further connected by wire 56 with the white light 57 and by wire 58 with the battery 41.

58' is a wire connecting the battery 41 with the solenoid switch 48.

59 is the red pencil mechanism connected by wire 60 with the red light 61 and to battery 41 by wire 62. 63 is a wire leading from the other pole of the red pencil mechanism to the danger signal contact 51.

Any suitable form of mechanism may be employed for holding and supporting the markers, which though herein referred to as pencils, may be any suitable device or implement capable of making a mark upon the rotary dial in connection with which they are employed. In Figs. 4 and 7 will be seen one efficient form of device for this purpose. It comprises an arm 64, one end of which is bifurcated, as seen at 65, forming resilient members 66 between which the marker 67 is held, the adjacent faces of the members 66 being concaved if desired to better receive the marker, and in order to prevent displacement of the marker by vibrations, the outer faces of the members 66 are serrated, as seen at 68, in Fig. 7, and a suitable clamping member or ring 69 is employed to embrace the members 66 and engage the serrations, the result of which will be obvious.

There are two markers, and consequently two marker-holders, but as the construction and operation are the same it is not necessary to particularly describe both, it 115 being sufficient to here state that said markers are designed to make different colored marks upon a rotary dial, the markers preferably being such as to make, one a red line and the other a blue. The arm 64 is pivotally mounted in a well known way, such for instance as indicated in Fig. 6 wherein it is shown as made most sensitive in its movements by being pivotally held upon the points of the adjusting screws 70 adjustably mounted in the opposite uprights 71 rising from the base 72, said uprights being joined at their upper ends by the cross piece 73. Seated in a recess in the upper face of this cross piece 73 is a bar 74 through which passes a screw 75 into the depending enlargement 76 of said cross piece, said screw having a polygonal head 77. The bar 64 carries the armature 78 for the magnets 79.

80 is a flexible plate secured at one end, as at 81, to the end of the bar 64 beyond its pivot, while its other end is secured, as at 82, to a flange 83 on a depending portion 84 of the bar 74, as seen clearly in Fig. 4.

5 85 are adjusting screws which extend through the bar 74 near opposite ends thereof, one engaging the plate 80, and the other the bar 64 at a point approximately in vertical line with the magnets 79. On these screws are the nuts 86. 87 is a metallic bar having a polygonal opening 88 to receive the corresponding head 77 on the screw 75, while at opposite ends it is formed with wrench-like members 89 which engage the nuts 86. 90 are jamb nuts on the screws 85 above the plate or bar 87. By this means the nuts 86 and consequently the screws 85 10 are effectually held against accidental movement by reason of the vibrations to which they are subjected.

The screws 85 are provided with milled heads 91 by means of which they can be adjusted to regulate and limit the amount of movement of the bar 64.

20 92 is a dial, preferably of paper, designed to be rotated by clockwork, in a well known way, and as no claim is herein made to the means for operating the dial no such mechanism has been illustrated. The dial is provided with graduations, so as to indicate not only 25 the hours but the minutes, and there are two concentric rows, 93 and 94, of such graduations, one to receive the markings of the red pencil, and the other those of the blue pencil, it being understood that said pencils are permanently fixed relatively to such annuli of graduations, as seen clearly in Figs. 1 and 2.

In practice, each engine is equipped, at any suitable point within the cab, with the mechanism hereinbefore described, Fig. 1 illustrating, diagrammatically, two such mechanisms. It is also designed that all signal 35 towers along the line shall be equipped with similar mechanism so that the operator in the tower can manipulate, through his closed circuit push button, the signals in the cab of the engine, or engines, and converse with the engineer, or engineers, through the telephone. It is designed that the dial and the marking 40 devices, as well as the solenoid and its switch and the small magnet 27, be arranged within a suitable metallic inclosure or box 95, shown as provided with lugs 96 by which it may be secured in any desired position within 45 the cab. The door 97 of this box is to be locked so that access thereto cannot be had by the engineer so that tampering with the record made on the dial is prevented. The bell 42, the galvanometer 32, and the telephone 37 and switch 34 may be arranged as may be found 50 most expedient with relation to the box 95 and its contained parts so also may the white and red lights 57 and 61.

It will be understood that a plurality of dials may be arranged upon the dial-support so that when one has 55 been used it may be removed and thus the next beneath it brought into operative position. The adjustment provided by the screws 85 compensates for the difference in height of the dial.

In connection with the hereinbefore described system, there is employed a switch signal as illustrated 60 in Figs. 13 and 14, referring to which, 1, 1, are the rails of the main track and 4 the third rail. 98 are the rails of the siding and 99 the third rail thereof. 100 is the third rail of the siding disposed between the wheel 65 rail 1 and the third rail 4 of the main track, being piv-

totally mounted at one end as 101, to the said wheel rail. The other end of said member 100 is connected to the switch plunger or rod 102, making its movement and position in perfect relation to the wheel switch. An inclined contact plate 103 is disposed alongside of 70 the third rail 4 of the main track and attached thereto. When the switch is closed the third rail member 100 is moved upon its pivot and thus breaks the contact; but when the switch is open this piece of rail 100 is forced upon the incline of the contact plate, thus short 75 circuiting the block, by connecting the positive current of the third rail with the negative of the wheel rail, so when an approaching train enters the block the engineer is automatically notified by the red light and bell in the cab that the switch is open. When the 80 switch is closed the white light only is shown in the cab. A wire 104 connects the third rail of the main track with the third rail of the siding, as seen in Fig. 13, so that when a train is on the siding the apparatus is in the same electrical relation with the main track as if 85 it were on the main road, thus giving the engineer warning that the track is clear before proceeding to open the switch and entering on the track.

The train can always be signaled by short circuiting from the third rail to the wheel rail with a wire or a 90 crowbar or analogous device which will show the red light and ring the bell in the cab when the engine enters the block.

With the parts constructed and arranged substantially as hereinbefore described, the operation, which 95 will be apparent from the foregoing description when taken in connection with the annexed drawings, is, briefly stated, as follows:—As seen in Figs. 1 and 2 the parts are in the position indicating safety. The switch 46 of the solenoid is on the contact point 50. The current is then from the safety point 50, by wire 52, contacts of the magnet 27, through wire 54, to the blue pencil mechanism, through the magnet thereof, thence by wire 56 to the white light 57, which remains lighted so long as the switch 46 is on the contact 50 and so long 100 as there is current in the primary circuit. The red light, in the mean time, is out and the bell is silent. When two engines approach each other sufficiently near to cut out all but one resistance 11, the current is increased to such an extent that the solenoid 29 is 105 energized, pulling in its core 49, and drawing the switch 46 from the contact point 50 over to the contact plate or point 51; this puts out the white light, and the red pencil mechanism is thrown into contact through point 51, wire 63, magnet 79 and the arm 64, which latter, 110 as it is attracted by the said magnet, brings the pencil 67 into contact with the rotating dial 92. Simultaneously the red light is thrown into circuit through wire 60 from the red pencil mechanism. The red light continues to burn and the red pencil to mark upon the 115 dial so long as the switch is on the contact point 51. Simultaneously with the throwing of the red light and red pencil into operative relation, the bell 42 commences to ring, through contact point 45, upon which the switch 46 is moved as it is moved upon the contact 120 point 51, and the wire 44. Indication of danger is thus given to both engineers simultaneously and automatically, whereupon both come to a stop. The engineer then opens his switch 34 and pushes his closed circuit push button 40, and telephones to the engineer on the 125 130

other engine. This continued pushing of the button 40 causes the red and white lights to flash alternately and the bell to jingle. The cause of the trouble can thus be determined. As soon as either engine moves 5 out of the block, the resistance then overcomes the current existing between the two engines, thereby allowing the balance spring of the switch 46 to pull the switch over from the contact point 51 to the contact point 50, thus putting out the red light and lighting 10 the white one, simultaneously the bell stops ringing and the magnet of the red pencil being no longer energized, the spring arm 80 withdraws the arm 64 upward so that the pencil is lifted from the dial 92. When the switch 46 is moved back into contact with the contact point 50, the magnet of the blue pencil is energized and the arm carrying said pencil is drawn down 15 so that the pencil is brought into contact with the dial 92 and commences to trace thereon. As soon as the red light is thrown out of circuit and the white light 20 thrown into circuit it indicates to the engineer in the cab that the danger is passed and the line is safe throughout the block in which his engine is located.

The system is operated by a closed circuit; the current is continually on, the strength being determined 25 by the distance between the trains. The current goes from the negative side of the primary batteries 26, by wire 36 to the contact 13, thence by the third rail 4, thence through the resistances 11 to the contact 13 of the approaching engine; thence by wire 36 to positive 30 side of batteries 26, from negative pole of said batteries to magnet 27 thence through the solenoid 29, galvanometer 32, switch 34 to wheel 2, thence along the wheel rail to the wheel 2 of the other engine, along wire 35 to switch 34 to wire 33 into galvanometer 32, 35 thence to wire 31 into solenoid 29 along wire 30 to release magnet 27, wire 28 to positive side of battery, showing batteries of both engines connected in series. It is evident that in lieu of the primary batteries I may sometimes employ a magneto generator.

40 From the above it will be seen I have devised an efficient and simple electric signaling system for railways, and while the structural embodiment of the invention as hereinbefore disclosed is what I at the present time consider preferable it is evident that the same 45 is subject to changes, variations, and modifications in detail without departing from the spirit of the invention or sacrificing any of its advantages. I therefore do not intend to restrict myself to the details of construction, proportion of parts, or relative arrangement 50 hereinbefore described, but reserve the right to make such changes, variations, and modifications as come within the scope of the protection prayed.

What is claimed as new is:—

1. An electric railway system embodying a third rail, resistances therein, a contact member carried by a moving part for contact with said third rail, differently colored lights on the engine, and a recording device having differently colored markers in circuit one with each of said lights.
2. An electric railway system embodying a third rail, resistances therein, a contact member carried by a moving part for contact with said third rail, differently colored lights on the engine, a recording device having differently colored markers in circuit one with each of said lights, and an audible signal in circuit with the red light.
3. An electric railway system embodying a third rail, resistances therein, a contact member carried by a moving

part for contact with said third rail, differently colored lights on the engine, a recording device having differently colored markers in circuit one with each of said lights, an audible signal in circuit with the red light, and a galvanometer. 70

4. An electric railway signaling system embodying a third rail, resistances therein, means for automatically alternately displaying differing visual signals, and means for simultaneously making a record thereof. 75

5. An electric railway signaling system embodying a third rail, resistances therein, means for automatically alternately displaying differing visual signals, means for simultaneously making a record thereof, and an audible signal actuated simultaneously with the visual signal. 80

6. In an electric railway signaling system, a current-supplying rail, a plurality of independently operable visual signals of different color, recording devices of different colors in circuit with said signals and an audible signal 85 simultaneously operable with one of said visual signals.

7. In an electric railway signaling system, a current-supplying rail, independently operable visual signals of different color, and recording devices one operable with each of said visual signals. 90

8. In an electric railway signaling system, a current-supplying rail, independently operable visual signals of different color, recording devices one operable with each of said visual signals, and means for throwing one of said recording devices out of operative position as the other is 95 thrown into operation.

9. In an electric railway signaling system, a current-supplying rail, independently operable visual signals of different color, recording devices one operable with each of said visual signals, and an audible signal operable with 100 one of said visual signals.

10. In an electric railway signaling system, a current-supplying rail, independently operable visual signals of different color, recording devices one operable with each of said visual signals, means for throwing one of said recording devices out of operative position as the other is 105 thrown into operation, and an audible signal operable with one of said visual signals.

11. In an electric signaling system for railways, a third rail having resistances therein, visual signals operable independently of each other, a rotary dial, and relatively fixed marking devices operable one in connection with each of said signals. 110

12. In an electric signaling system for railways, a third rail having resistances therein, visual signals operable independently of each other, a rotary dial, relatively fixed marking devices operable one in connection with each of said signals, and means for throwing one of said marking devices out of operative position as the other is thrown into operation. 115

13. In an electric signaling system for railways, a third rail having resistances therein, a rotary dial, differently colored markers for coöperation therewith, a solenoid and a switch operable in connection therewith, and an inclosing casing therefor. 120

14. In an electric signaling system for railways, a third rail having resistances therein, a rotary dial, differently colored markers for coöperation therewith, a solenoid and a switch operable in connection therewith, an inclosing casing therefor, and differently colored lights operatively connected with said markers. 125

15. In an electric signaling system for railways, a third rail having resistances therein, a rotary dial, differently colored markers for coöperation therewith, a solenoid and a switch operable in connection therewith, an inclosing casing therefor, and an audible signal controlled by said switch. 130

16. In an electric signaling system for railways, a third rail having resistances therein, a rotary dial, differently colored markers for coöperation therewith, a solenoid and a switch operable in connection therewith, an inclosing casing therefor, differently colored lights operatively connected with said markers, and an audible signal controlled by said switch. 140

17. In an electric signaling system for railways, a third rail having resistances therein, a rotary dial, differently colored markers for coöperation therewith, a solenoid and

- a switch operable in connection therewith, an inclosing casing therefor, differently colored lights operatively connected with said markers, and a galvanometer in the circuit.
- 5 18. In an electric signaling system for railways, a third rail having resistances therein, a rotary dial, differently colored markers for coöperation therewith, a solenoid and a switch operable in connection therewith, an inclosing casing therefor, an audible signal controlled by said switch, and a galvanometer in the circuit.
- 10 19. In an electric signaling system for railways, a third rail having resistances therein, a rotary dial, differently

colored markers for coöperation therewith, a solenoid and a switch operable in connection therewith, an inclosing casing therefor, differently colored lights operatively connected with said markers, an audible signal controlled by said switch, and a galvanometer in the circuit. 15

Signed by me at Washington this 18th day of January 1907.

HARRY J. WARTHEN.
